FLASHLIGHT ADAPTER FOR MARINE
RUNNING LIGHTS

George Washington Trahey, Bremerton, Wash.

Application December 20, 1932
Serial No. 648,126

6 Claims. (Cl. 240—7.5)

This invention relates to marine running lights and more particularly to a means for adapting a flashlight for use as a marine running light.

An object of this invention is to provide an attachment which can be mounted on any conventional flashlight casing or housing which will transform or convert the flashlight to a marine running light which in turn will meet the regulations relating to such lights.

Another object of this invention is to provide an exceedingly simple attachment of this kind which is so constructed that it can be mounted at any desired position on the boat and which when in mounted position will produce a light fully complying with the marine regulations relative thereto.

The above and various other objects and advantages of this invention will in part be described and in part be understood from the following detailed description of the present preferred embodiment, the same being illustrated in the accompanying drawing wherein:—

Figure 1 is a detail side elevation partly broken away of a device constructed according to the preferred embodiment of this invention.

Figure 2 is an enlarged fragmentary top plan view of the device with the colored plate holding cover removed therefrom.

Figure 3 is a top plan view of the plate holding cover.

Figure 4 is a fragmentary sectional view taken on the line 4—4 of Figure 1.

Referring to the drawing wherein like numerals designate corresponding parts throughout the several views, the numeral 10 designates generally a flashlight casing or housing of conventional construction which is provided with the usual lens, reflector and light bulb (not shown.) The housing or casing 10 is also provided with the usual flashlight battery cells connected to the lamp circuit and which is closed by the usual switch. The casing 10 has a threaded bezel 11 engaging about the lens and the reflector. In the present instance, this bezel has a hexagonal outer rim portion 13 and is provided with the usual round opening through which the light is projected from the light bulb carried by the casing 10.

In order to adapt the flashlight 10 for use as a marine running light, I have provided a vane or partition 12 which extends forwardly of the bezel 11 in alignment with the longitudinal axis of the flashlight 10 and the longitudinal axis of the bezel 11 and divides the light beams passing

55 through the bezel 11 into two parts. A base

plate 14 is secured to the lower edge of the dividing wall 12 and is of a width substantially equal to the diameter of the bezel 11, and acts to prevent the forwardly projecting rays from striking the ground or water at a point closely adjacent the boat or the like. A rear wall 15 is formed with or integral with the base plate 14 and is provided with a round opening 16 substantially equal to the opening in the bezel 11, and this back plate 15 is adapted to engage against and be secured to the forward side of the bezel.

In order that different colored light rays will be projected forwardly of the flashlight 10 such as red and green, one color on each side of the partition or dividing member 12, I have provided a substantially U-shaped guide member 17 on each side of the dividing wall 12 in a position forwardly of the bezel 11, and the opposite edges of the back plate 15 are bent forwardly, as at 18, to provide a rear guide member to receive a colored light transmitting plate 19. The bottom edge of each plate 19 rests on top of the base 14 while the vertical edges thereof engage the vertical guides 17 and 18, respectively. Each plate 19 extends forwardly of the back plate 15 on an angle to the longitudinal axis of the dividing wall 12.

In order to prevent loss of the plates 19, I have provided a substantially triangular extension 20 which is integral with the back wall 15 and extends in a direction parallel to the base 14. This extension 20 is provided on two sides thereof with depending flanges 21 which are adapted to engage against the inner surfaces of the plates 19 adjacent the top thereof, and a cap or top piece 22, having depending flanges 23, engages over the plate or extension 20 and the flanges 23 are adapted to engage against the outer surfaces of the plates 19 so that the plates 19 will be held against movement within the grooves 17 and 18. The plate or extension 20 is provided with threaded apertures 24 and in like manner, the cap or top plate 22 is provided with apertures 25 to receive securing members 26 in the form of screws, bolts or the like.

The flashlight 10 is supported on the desired part of the vessel or boat by means of a standard 27 which has a horizontally disposed member 28 on the upper end thereof, and this member 28 is provided with a pair of spaced loops 29 engaging about the periphery of the flashlight housing 10 so as to hold this housing against circumferential and longitudinal movement relative to the flashlight support.

In the use and operation of this device, the

standard or bracket 27 may be mounted in the desired position on the vessel, boat or the like, and the flashlight housing 10 secured thereto with the vane or dividing member 12 positioned 5 in substantially a vertical position parallel with the length of the boat. The light beams projected through the plates 19 on one side will be hidden from a point forwardly and to one side of the flashlight a distance required by the marine regulations. A person positioned directly 10 in front of the two plates 19 will observe the red and green lights and in this manner will know that he is directly in front of the light, whereas if only one color is distinguished, the person will 15 know that he is on one side of the approaching vessel, in a manner set forth in the existing regulations.

It will be obvious from the foregoing that an 20 adapter has been provided for a flashlight of conventional construction which can be detachably mounted on the flashlight housing and when it is desired to use the flashlight for other purposes, the housing 10 can be removed from the bracket or standard 27 and the head taken off 25 therefrom and the usual bezel and lens inserted in place of the structure hereinbefore described.

However, when it is desired to convert the 30 flashlight into a marine running light, the conventional head including the bezel and lens can be removed and the attachment herein described mounted on the casing 10. The attachment herein described can be used either with or without the usual lens provided for a flashlight, in view of the fact that the plates 19 are positioned 35 forwardly of the end of the flashlight housing 10 and as the divergent or inner ends of the plates 19 are positioned on each side of the bezel, it will be obvious that the ordinary lens provided with the flashlight may be used in combination with 40 the structure herein described.

It is, of course, understood that various 45 changes and modifications may be made in the details of construction and design of the above specifically described embodiment of this invention without departing from the spirit thereof, such changes and modifications being restricted only by the scope of the following claims.

What is claimed is:—

1. An adapter as set forth comprising a bezel 50 adapted to engage a flashlight casing, a plate extending forwardly of the bezel in alinement with the longitudinal axis of the flashlight, a second plate secured to one edge of the first plate and positioned at a right angle thereto, a pair of 55 guide members secured one on each side of the first plate forwardly of the bezel, guide members positioned adjacent the forward edge of the bezel and disposed rearwardly of the first named guide members, a colored plate of light transmitting characteristics in each confronting pair of

guide members, and means for securing the colored plates in the guide members.

2. As a new article of manufacture an attachment for a flashlight comprising an annulus, an opaque plate secured to said annulus and extending longitudinally of the axial center of the annulus and dividing the annulus into equal parts, a pair of colored light transmitting plates and coacting guide means carried by the annulus and the first plate to hold the two colored plates in forwardly convergent position. 80 85

3. As a new article of manufacture an attachment for a flashlight comprising an annulus, an opaque plate secured to said annulus and extending longitudinally of the axial center of the 90 annulus and dividing the annulus into equal parts, a pair of colored light transmitting plates, coacting guide means carried by the annulus and the first plate to hold the colored plates in forwardly convergent position, and a base plate secured 95 to one edge of the first plate and having one edge abutting against said annulus.

4. As a new article of manufacture an attachment for a flashlight comprising an annulus, an opaque plate secured to said annulus and extending longitudinally of the axial center of the annulus and dividing the annulus into equal parts, a pair of colored light transmitting plates, coacting guide means carried by the annulus and the first plate to hold the colored plates in forwardly convergent position, a base plate secured 100 to one edge of said first plate and the annulus and disposed at a right angle to said first plate, and a cap engaging said guide means and said colored plates to hold said colored plates against 105 movement in said guide means.

5. An adapter as set forth comprising a bezel 115 adapted to engage over one end of a flashlight casing, a plate secured to the bezel and extending forwardly therefrom in alinement with the longitudinal center of the bezel, a colored light transmitting plate on each side of the first mentioned plate, and means for securing the colored plates one on each side of said first plate in the path 120 of light rays passing through said bezel.

6. An adapter for converting a flashlight into 125 a marine running light comprising a bezel adapted to engage the flashlight casing, an opaque plate extending in a direction substantially in alinement with the axial center of the bezel, a pair of light transmitting plates one on each side of 130 said first plate, a base plate secured to said first plate and positioned at a substantially right angle thereto, and means for securing a colored plate of light transmitting characteristics on each side of the first plate and on an angle to said first plate. 140
